UNITED STATES PATENT OFFICE

2,189,384

RAILWAY CAR END STRUCTURE

Edgar E. Schlesinger, Chicago, Ill., assignor to
Standard Railway Equipment Manufacturing
Company, Chicago, Ill., a corporation of Dela-
ware

Application January 14, 1938, Serial No. 185,025

4 Claims. (Cl. 105—410)

The invention relates to railway house cars, such as box, automobile and refrigerator cars, and has for its object to provide very strong corner posts for use with a car end wall made of 5 relatively thin metallic sheets and provided with a plurality of substantially parallel horizontal corrugations, which corrugations form a plurality of beams between the opposite corner posts of the car to resist a shifting load and to keep 10 the car in square. More specifically the object of the invention is to provide a corner post which is so formed and has its opposite ends so secured to the roof structure and underframe structure, respectively, as to provide a very strong semi- 15 restrained beam between these structures to resist forces in any horizontal direction and to secure the corner posts to these structures so as to prevent it from rotating about its vertical axis, or as it is called, to resist torque. 20 A shifting load in a railway freight car exerts a horizontal force against the end wall and if the end wall deflects outwardly the middle portions of the corner posts are pulled inwardly, while the tops and bottoms, respectively, of the 25 corner posts are held in position and prevented from coming toward each other by the end plate and end sill, respectively, thus causing a bowing or horizontal beam action on each corner post. Railway cars are frequently "cornered" in service; 30 that is, some outside object is thrown against the corner post (or the car is thrown against the outside object) causing a horizontal force to be exerted toward the inside of the car.

Each corner post is also a strut of the over- 35 hanging portion of the side truss of the car; (that is, the portion beyond the body bolster) and as such must act as a column or compression member between the side plate and side sill of the car.

A further object is to associate the vertical 40 marginal portion of the corrugated metallic sheet end wall with a vertically disposed member to form a column comprising angularly disposed arms reinforced by arched ties, which column extends between the roof structure and the underframe structure and functions as a corner post to resist the forces heretofore mentioned, and a further object is to attach the ends of the corrugations (in the end sheet) to the opposite 45 corner posts so as to cause the corrugations to function as restrained, or semi-restrained beams, thus materially increasing their strength.

A further object is to extend the corrugations in the above mentioned corrugated metallic sheet end wall so that any load imposed thereon is 50

transmitted partially to the vertical member adjacent the inner margin thereof and partially to the vertical member adjacent the outer margin thereof, and a further object is to reinforce such outer margin by rigidly securing it to the side 5 wall sheathing.

A further object is to secure one of the elements of the corner post to the metallic side wall sheet so as to obtain cooperation therebetween to resist the various stresses to which a car is 10 subjected in service.

A further object is to associate the corrugations with the corner post so as to transmit at least a part of the stresses imposed thereon to the side 15 wall sheet.

A further object is to form the vertical marginal portion of the corrugated end wall sheet with a lateral flange formed on a relatively large radius to form in effect an arch between the vertical margins of the inside vertical member 20 to resist exterior horizontal forces. Such large radius would also enhance the appearance of the car.

In the drawing:

Fig. 1 shows a typical end wall for a railway 25 car made of a metallic sheet formed with a plurality of horizontally disposed corrugations with the end wall thereof attached to one modification of my improved corner post.

Fig. 2 is a fragmentary side view of the car 30 shown in Fig. 1.

Fig. 3 is an enlarged section on line 3—3 of Fig. 1 showing a typical form of my improved post.

The drawing shows the usual parts of the car, 35 such as the roof structure 1 (including the side plates 2; end plates 3 and roof proper 4 and other associated elements); the underframe structure 6 (including the side sill 7; end sill 8; center sill and other associated elements); side 40 wall sheet 10; side lining 11; side lining nailing strip 12 and end lining 13.

The vertical member 15 comprises angularly disposed arms 16—17 preferably provided with reflanges 18—19. The arms 16—17 are preferably each secured to the roof 1 and underframe structures 6 and the reflanges 18—19 are also each preferably secured to the roof 1 and underframe structures 6.

The end wall sheet 20 extends between opposite 50 vertical members 15—15 and is secured to the arms 17 thereof by the reflanges 19 and the rivets 21. The vertical margin of the end wall sheet is formed with a flange 22 which is secured to the arm 15 by the reflange 18 and the rivets 23. The 55

arms 16 and 17 with the flange 22 and the adjacent part 24 of the end wall sheet 28 are thus combined to form a box structural corner post or beam between the roof and underframe structures of the car.

The end wall sheet 28 is formed with a plurality of substantially parallel horizontally disposed corrugations or embossments 26 which traverse the end wall sheet 28 between the opposite corner posts of the car which corrugations or embossments extend around the corner of the car to the edge 25 of the flange 22. The end wall sheet 28 is preferably formed with other horizontal corrugations 27 between the corrugations 26 which spring from the body of the end wall sheet (at 28) and extend around the corner of the car and merge into the flange 22 (at 29) of the end wall sheet 28.

The connecting piece 33 is provided with a flat vertical margin 34 secured to the side wall sheet 18 of the car by the rivets 35 and a corrugated vertical marginal part 36 which registers with the corrugations in the flange 22 of the end wall sheet 28 and is secured thereto preferably by welding 37 to form a weatherproof connection. Thus part of the load imposed upon the corrugations 26 and 27 is transferred to the side wall sheet 18.

The side wall sheet 18 is preferably in the same plane as the outer portions of the corrugations 26-27 in the flange 22 to provide a flush side wall. The end wall sheet flange 22 preferably overlaps the connecting piece 33 to provide a shingle construction and to facilitate removal of the end wall sheet independently of the connecting piece.

This application is assigned to Standard Railway Equipment Manufacturing Company, a corporation of Delaware, and Mr. Gilpin's one-half undivided right, title and interest in Jumper and Gilpin application No. 194,360, filed March 7, 1938, is also assigned to said Standard Railway Equipment Manufacturing Company, therefore, under Rule 43 reference is made herein to the fact that certain structures are disclosed in this

application which are disclosed and claimed in the aforesaid Jumper and Gilpin application.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a railway car having a roof structure, an underframe structure and a side wall sheet in combination with a vertical member secured to the roof structure and underframe structure, respectively, and comprising angularly disposed arms, an end wall sheet secured to one arm of said member and provided with a flange secured to the other arm of said member, said end wall sheet formed with a plurality of horizontal corrugations which traverse the end wall sheet and extend to the edge of the flange whereby said corrugations function as arched ties between said arms to prevent deflection thereof, and a connecting piece having a flat vertical marginal part secured to said side wall sheet, and a corrugated vertical marginal part registering with the corrugations in the end wall sheet and secured thereto.

2. A structure as defined in claim 1 wherein the side wall sheet is substantially in the same plane as the outer portions of the corrugations in said end wall sheet flange.

3. A structure as defined in claim 1 wherein the end wall sheet is formed with other horizontal corrugations between the first mentioned corrugations which extend around the corner of the car and merge into the flange of the end wall sheet.

4. A structure as defined in claim 1 wherein the end wall sheet is formed with other horizontal corrugations between the first mentioned corrugations which spring from the body of the end wall sheet and extend around the corner of the car and merge into the flange of the end wall sheet.

EDGAR E. SCHLESINGER. 45
